UNITED STATES PATENT OFFICE.

JOHN G. HODGSON, OF MAYWOOD, ILLINOIS, ASSIGNOR TO AMERICAN CAN COMPANY, OF NEW YORK, N. Y., A CORPORATION OF NEW JERSEY.

CQNTAINER.

1,332,839.

Specification of Letters Patent.

Patented Mar. 2, 1920.

Application filed September 14, 1914, Serial No. 861,534. Renewed January 24, 1920. Serial No. 353,812.

To all whom it may concern:

Be it known that I, JOHN G. HODGSON, a citizen of the United States, residing in Maywood, in the county of Cook and State 5 of Illinois, have invented a new and useful Improvement in Containers, of which the following is a specification.

My invention relates to the manufacture and use of containers and the like and more 10 particularly to the manufacture and use of sheet metal containers in the canning industry.

In canning vegetables and other foodstuffs of various kinds it is a custom to cook the 15 materials after they have been placed in the cans in which they are to be sold to the trade. In order that the materials being canned may be properly preserved, the cans are permanently and hermetically closed 20 during or immediately after the cooking process in order to prevent the entrance of germs and ferments.

It has frequently been the custom prior 25 to my invention to permanently close the cans either by seaming or by plugging vents immediately upon the termination of the cooking step and to then lacquer the seam of closed vents while the can is still extremely hot and before any contraction of the material takes place. This process has been 30 found efficient when used in canning foodstuffs wherein the period of heating or cooking need not be accurately determined and observed. In the canning of peas and other 35 vegetables, however, where the quality of the cooked product depends in great degree upon the sudden cooling of the can and consequent termination of the cooking step, the method has not been found so satisfactory.

40 In cooking peas and the like it is the custom to immerse the cans in cool or cold water as soon as they are received from the cooking chamber, insufficient time being given to apply the coating of lacquer.

45 It is a purpose of this invention to provide means for hermetically sealing the can during the cooking or processing operation so that it will not be necessary to wait until after the can has come from the cooking 50 chamber.

It is a principal object of the present invention to provide an improved hermetic seal which automatically applies itself during the processing of a container or can.

55 A further object of the invention is the

provision of a container provided with means for forming a hermetic seal between its body and closure or end, which will require no manipulation by the packer or canner other than seaming the container in the 60 ordinary manner.

Other objects and advantages of the invention will be apparent as it is better understood from the following description when considered in connection with the accompanying drawing illustrating a preferred embodiment thereof.

Referring to the drawing,

Figure 1 shows a can or container embodying my invention and hermetically sealed; 70

Fig. 2 is a side elevation of a can body embodying my invention;

Fig. 3 is a transverse section of an end or closure for the same; and

Fig. 4 is a partial transverse sectional 75 view showing the closure and an end of the body seamed together.

For the purpose of illustrating my invention I have shown it embodied in a can of an ordinary and well known type in which the 80 ends and body are joined by a double seam.

The can body 5 in the present instance is provided with outwardly extending flanged end edges 6 of the ordinary type adapted to be turned over, as seen in Fig. 4, in forming the double seam. On the under side of these flanges and extending longitudinally of the body is painted or otherwise provided a film or coating 7 of some gummy material adapted to expand and soften under heat. 90

The extent of this film or coating is preferably such that when the seam is formed the coating will terminate at or about the seam, as seen at 8 in Fig. 4. The cover or end 9 in the present instance is provided with an 95 outwardly extending flange 10 turned down slightly at its edges 11 in the ordinary manner. The usual packing 12 is provided on the under side of the flange 10. On the upper surface of this flange and adjacent 100 its edge is provided, if desired, a coating or film 13 of material similar to that forming the coating or film 7. However, it will be manifest, as the invention is better understood, that either the film 7 or the film 13 105 may be omitted. Films 7 and 13, after being placed on the can, are permitted to dry and they form little more than a coat of lacquer of the ordinary thickness in their dried condition.

When the can is seamed it will be 11

noted that the coating 7 on the can body is brought opposite the adjacent surfaces of the cover and the coating 13, if used, is brought opposite the adjacent surface of the can body. These coatings are provided and are substantially dried before the ends are secured to the body and they may be provided, if desired, on the blanks before the ends or body are formed. When the can has been seamed and is hot from processing or in processing, the lacquer softens and swells and forms a film adhering to the adjacent surfaces of the body and cover to form a hermetic seal.

15 In practice it is customary to secure one end to the can body at the can factory and to supply the other end free of the can to subsequently be positioned and attached by the packer or canner.

20 Where cans are provided embodying my invention one end may be completely sealed in the manner described and the can furnished with a lacquer coating or film at the other end of the can body or on the outer 25 surface of the other end closure or both, it only being necessary for the canner or packer to fill the can with its contents and process it in the usual manner, the resulting product being hermetically sealed without 30 the necessity of subsequently lacquering the can in the manner earlier described. A can embodying my invention filled and sealed in proper manner will hide completely the lacquer film and an article more pleasing in 35 appearance is thereby produced than is possible where the lacquer is painted over the seamed edge after processing.

It is thought that the invention and many of its attendant advantages will be understood from the foregoing description, and it will be apparent that various changes may be made in the form, construction and arrangement of the parts without departing from the spirit and scope of the invention 45 or sacrificing any of its material advantages, the form herein described being merely a preferred embodiment thereof.

I do not claim herein the method which is described, the same being the subject of my 50 application Serial No. 88,503, filed April 3, 1916.

I claim:

1. A flanged container body provided on the under side of its flange with a dried 55 film of gummy material, and also provided on its vertical sides adjacent said flange with a dried film of said material; and a flanged cover provided with a packing material on the under side of the flange, and 60 also provided with a dried film of said gummy material on that portion of the top

of its flange which is brought into contact with the said film of gummy material on the vertical sides of the can when the cover is double seamed to the can.

2. A container body provided adjacent its end edges with a dried film of gummy material adapted to expand under heat and to adhere to the edges of a closure subsequently fixed in place and to form a hermetic seal 70 therewith, said film extending over the outer surface of the vertical portion of said body adapted to contact with said cover.

3. A container comprising a body and an end closure having adjoining edges adapted 75 to be seamed together, a dried film of gummy material on a vertical portion of the body which contacts with the cover in seaming, said film being expandable under heat and adapted to adhere to the contacting 80 portion of the cover to form a hermetic seal.

4. A container comprising a body and an end closure having adjoining edges adapted to be seamed together, and a dried film of gummy material on the top portion of the 85 cover which contacts with the body in seaming, said film being expandable under heat and adapted to adhere to the body to form a hermetic seal.

5. A container comprising a body and an 90 end closure having adjoining edges adapted to be seamed together, and dried films of gummy material on both of the opposed portions of said body and cover which contact in seaming, said films being expandable 95 under heat and adapted to adhere together to form a hermetic seal.

6. A container comprising a body and an end closure having adjoining edges adapted to be secured together, and a coating of 100 lacquer on a vertical portion of the body which contacts with the cover in seaming.

7. A flanged can body for a double seam closure, the same being provided on its vertical sides, which are not bent into the 105 double seam but which are engaged by the top parts of the cover when the double seam is formed, with a dried film of gummy sealing material.

8. A flanged can cover for a double seam 110 closure, the same being provided on its top side near its edge, with a dried film of gummy sealing material which is adapted to be brought into tight contact with the vertical sides of the can, when the double 115 seam is formed.

Signed this 25th day of August, 1914, in the presence of two witnesses.

JOHN G. HODGSON.
